Patented May 20, 1969

214.213

FLASHLAMP MOUNTING UNIT

Wallace A. Monson, Golden Valley, Minn., assignor to
Honeywell Inc., Minneapolis, Minn., a corporation of
Delaware

Filed Jan. 8, 1968, Ser. No. 10,082

Term of patent 14 years

Int. Cl. D26—99; D16—07

FIG. I

FIG. 2

FIG. 3

FIG. 5

FIG. 4

FIG. 1 is a front, top perspective view of a flashlamp mounting unit showing my new design;

FIG. 2 is a perspective view of the flashlamp mounting unit taken below the unit shown in FIG. 1 with the mounting shoe thereof extended for tilting the unit:

FIG. 3 is front elevational view of the flashlamp mounting unit shown in FIG. 1;

FIG. 4 is a side elevational view showing the side of the flashlamp mounting unit illustrated in FIG. 3; and

FIG. 5 is a rear view of the flashlamp mounting unit shown in FIG. 4.

I claim:

The ornamental design for a flashlamp mounting unit, as shown.
